SPRAYER FOR LIQUIDS OR THE LIKE

John G. Ellis, Shaker Heights, Ohio, assignor to Sprayon Products, Inc., Cleveland, Ohio, a corporation of Ohio

Application February 6, 1959, Serial No. 54,494

Term of patent 14 years

(Cl. D62—2)

The dominant features of the design reside in the portions shown in full lines.

I claim:

The ornamental design for a sprayer for liquids or the like, as shown and described.
